(57) **ABSTRACT**

In example implementations, a method is provided. The method includes determining, by a processor, that a vehicle is approaching a door of a building based on a velocity vector of the vehicle, calculating, by the processor, a time of arrival of the vehicle at the door based on the velocity vector of the vehicle and a distance of the vehicle from the door, and controlling, by the processor, the door to begin opening at a time based on the time of arrival and an amount of time for the door to open such that the door is opened when the vehicle arrives at the door.

APPARATUS AND METHOD FOR DOOR CONTROL

CROSS-REFERENCE TO RELATED APPLICATIONS

This application is a continuation-in-part of U.S. patent application Ser. No. 16/741,900 filed on Jan. 14, 2020, which is hereby incorporated by reference in its entirety.

BACKGROUND

Certain enterprise locations may use large doors that can be opened and closed as traffic comes into and out of the enterprise location. For example, industrial warehouses may have vehicles and people that frequently go in and out of the warehouse through certain doors. For a variety of different reasons (e.g., energy savings, security, and the like), the doors cannot remain opened. As a result, each time a vehicle or person goes through the door, the door is opened and closed.

The doors may include rolled steel doors that may be relatively heavy. The doors may take several seconds to open and close. Thus, each time an operator on a vehicle arrives at a door, the operator may wait several seconds for the door to open. Over a course of a working day, several weeks, and a year, this may add up to a large amount of time wasted on waiting for the door to open.

BRIEF DESCRIPTION OF THE DRAWINGS

FIG. 1 is a block diagram of a top view of an example system for automated door control of the present disclosure;

FIG. 2 is a block diagram of an example apparatus for automated door control of the present disclosure;

FIG. 3 is a block diagram of an example of the system for automated door control in operation;

FIG. 4 is a flow chart of an example method for controlling a door of the present disclosure; and

FIG. 5 is a block diagram of an example non-transitory computer readable storage medium storing instructions executed by a processor to control a door of the present disclosure.

DETAILED DESCRIPTION

Examples described herein provide a system, apparatus, and method to automatically control a door. As noted above certain locations (e.g., industrial warehouses) may have vehicles and people that may frequently go into and out of the location via certain doors. However, for a variety of different reasons, the doors cannot remain open.

The doors may include commercial steel rolled doors that are relatively large and heavy. There are some automated systems to control operation of the commercial steel rolled door. However, these current systems require an operator to arrive at the door and then wait for the door to open. This can take several seconds. Over the course of a day, week, or year, the several seconds can add up to a large amount of time that is wasted on waiting for the door to open and close.

Examples herein provide a system that can automatically open and control a door based on a velocity of an approaching vehicle. For example, the system may include a network of sensors that can gather position information of the vehicle and then calculate how quickly the vehicle is moving. Based on the velocity of the vehicle, the system may automatically

cause a door to begin opening such that the door is open when the vehicle arrives at the door.

Controlling the door based on the velocity of the approaching vehicle may also prevent the collisions between the door and the vehicle. For example, controlling the door based on the velocity of the approaching vehicle may prevent the door from crashing on the vehicle or the vehicle from crashing into the door.

The system may also include a virtual lane that includes an area where the velocity calculations may be initiated. The virtual lane may prevent false open signals (e.g., when a vehicle is approaching a shelf near the door, but not going out of the door). The virtual lane may also provide additional safety (e.g., when there is two way traffic through a door, the virtual lane may ensure the vehicle is exiting on the correct lane or side of the door).

FIG. 1 illustrates an example system 100 of the present disclosure. In one embodiment, the system 100 may be deployed in a location 114. The location 114 may be an enterprise location such as an industrial warehouse. The location 114 may have a door 104 that is controlled by a motor 150. The door 104 may be a steel rolled door that can be opened and closed by operation of the motor 150.

Although a single door 104 is illustrated in FIG. 1, it should be noted that the location 114 may include a plurality of different doors 104 at different locations around the location 114. Thus, the automated door control described herein may apply equally to any door 104 at the location 114.

In one embodiment, the system 100 may include a controller or server 102 that is communicatively coupled to the motor 150. The controller 102 may automatically activate or deactivate the motor 150 to open and close the door 104. As noted above, the location 114 may include many different doors 104 with respective motors 150. The controller 102 may be communicatively coupled to each door 104 or a plurality of controllers 102 may be deployed such that each door 104 is coupled to a respective controller 102.

In one embodiment, the system 100 may include a plurality of sensors 106₁ to 106₆ (also referred to herein individually as a sensor 106 or collectively as sensors 106). Although six sensors 106 are illustrated in FIG. 1, it should be noted that any number of sensors 106 (e.g., more than six or less than six) may be deployed.

In one embodiment, the sensors 106 may be any type of sensor that can collect, capture, measure, and the like, movement data and/or information associated with a vehicle 108. The vehicle 108 may be any type of motorized or non-motorized vehicle. For example, the vehicle 108 may be a driven forklift, a manually pushed hand cart, a motorized cart or car, and the like.

In one embodiment, the sensors 106 may be motion sensors that use a laser to measure time of flight. In one example, the sensors 106 may be image capturing devices. For example, an image capturing device may be a video camera that can capture consecutive images or motion video. The images or motion video may then be analyzed using available motion or image analysis techniques to calculate movement data of the vehicle 108.

In one embodiment, the sensors 106 may be communicatively coupled to the controller 102. The sensors 106 may be communicatively coupled to the controller 102 via a wired or wireless connection. Examples of wireless connections may include Wi-Fi, Bluetooth, Zigbee, and the like.

In one embodiment, the sensors 106 may accurately track positioning of equipment or objects in the location 114 using an ultra-wideband (UWB) protocol. For example, the sensors 106 may use time of flight (TOF) or transit time

methodology versus measurements of signal strength used in other types of sensors. The vehicle **108** may include a tag that can operate on battery power or power drawn from the vehicle **108**. The tags can send information periodically to the sensors **106** that are in a fixed position. The running time of the light from the tag to the sensors **106** may use UWB for transmission. One or more sensors **106** can then calculate the distance of the vehicle **108** based on the information or light sent by the tag on the vehicle **108**.

In one embodiment, with UWB technology, the distance between each sensor and each tag can be measured. The position coordinates of the vehicle **108** may then be calculated using a positioning algorithm and the distance between the tag and each sensor. With a variation of the coordinates, the movement of the tag on the vehicle **108** can be determined. The movement may include a velocity and a direction of the movement, as discussed in further details below.

In one embodiment, the controller **102** may receive data from the sensors **106**. The controller **102** may then perform analysis on the data to determine whether to automatically open the door **104**, as discussed in further details below. In one embodiment, the controller **102** may activate the motor **150** at a particular time to begin opening the door such that the door is open when the vehicle **108** arrives at the door **104**. In other words, the controller **102** may control operation of the door **104** such that when the vehicle **108** intends to exit the location **114** through the door **104**, the vehicle **108** may do so without waiting or stopping for the door **104** to open. Said another way, the door **104** may be opened to account for an amount of time to open the door **104** and a speed of the vehicle **108** such that the vehicle **108** may exit the location **114** without waiting. The calculations and analysis performed by the controller **102** to control operation of the motor **150** and the door **104** are discussed in further details below.

In one embodiment, system **100** may include a radio frequency (RF) tag reader **112**. Although a single RF tag reader **112** is illustrated in FIG. 1, it should be noted that any number of RF tag readers **112** may be deployed in the location **114**. The RF tag reader **112** may be communicatively coupled to the controller **102** via a wired or wireless connection. For example, the RF tag reader **112** may also be communicatively coupled to the controller **102** via a wireless protocol such as Zigbee or Wi-Fi.

The RF tag reader **112** may read an RF tag **110** located on the vehicle **108**. The RF tag **110** may be a powered or a passive RF tag that contains information associated with the vehicle. The information may include a type of vehicle (e.g., a forklift, a motorized cart, a hand cart, a crane, and the like), which department the vehicle belongs to, security information associated with the vehicle, and the like. In one embodiment, the RF tag **110** may also function as the tag that emits light or information to the sensors **106** using UWB to calculate a time of flight, as described above.

In one embodiment, the RF tag reader **112** may read the RF tag **110** and send the information to the controller **102**. The information may be used to determine if the vehicle **108** is authorized to exit through the door **104**. Thus, if the vehicle **108** is not authorized, the controller **102** may prevent the door **104** from opening.

The information may also be used to provide other types of information. For example, the information may include vehicle information or operator information. The information may include an Internet protocol (IP) address of a communication module on the vehicle **108**. As a result, if the vehicle **108** is moving too quickly, the controller **102** may send a signal or message to the vehicle **108** via the IP

address. In another example, if the door **104** is malfunctioning or offline for maintenance, the controller **102** may send a message to the vehicle via the IP address read from the RF tag **110**.

5 In one embodiment, the system **100** may include a virtual lane **120**. The virtual lane **120** may be a predefined area where, upon detection of the vehicle **108** in the virtual lane **120**, the controller **102** may begin analyzing the data received from the sensors **106**. The controller **102** may 10 calculate a velocity vector **116** and determine if the vehicle **108** is attempting to exit the location **114** via the door **104**. As discussed in further details below, the velocity vector **116** may include a velocity component and a directional component. The directional component may indicate the intention of the vehicle **108**.

15 If the controller **102** determines that the vehicle **108** is attempting to exit or enter through the door **104**, the controller **102** may also calculate a distance **118** of the vehicle **20** from the door **104**. Based on the velocity vector **116**, the distance **118**, and an amount of time to open the door **104**, the controller **102** may calculate a time at which the controller **102** may activate the motor **150** to begin opening the door **104**.

25 To illustrate, the vehicle **108** may be moving at 10 meters per second (m/s). The vehicle **108** may be approximately 100 meters from the door **104**. The door **104** may take 4 seconds to open. Thus, the vehicle **108** may arrive at the door **104** in 10 seconds. Thus, the controller **102** should activate 30 the motor **150** to begin opening the door **104** in 6 seconds, such that the door **104** is completely opened when the vehicle **108** arrives at the door **104** in 10 seconds.

35 In one embodiment, the virtual lane **120** may allow the controller **102** to operate more efficiently. For example, the sensors **106** may be continuously collecting movement data/information from a plurality of different vehicles **108**. For example, although a single vehicle **108** is illustrated in FIG. 1, a plurality of vehicles **108** may be present and moving simultaneously in the location **114**. The sensors **106** 40 may collect movement data from the vehicles and send the data to the controller **102**.

45 The virtual lane **120** may also allow movement information of vehicle **108** to be filtered and/or simplified to velocity vectors to regulated lanes. Filtering may account for measurement error from the sensors **106** and human driving deviations or errors. The movement information along the virtual lane **120** can be used to determine the intention of the driver. This may help to reduce the data obtained from the sensors **106**.

50 Without the virtual lane **120**, the controller **102** may be required to continually process thousands of data points of many different vehicles. This can require a large amount of processing power and consume large amounts of energy. However, in the present disclosure, the controller **102** may be activated to begin performing calculations when the vehicle **108** is detected within the virtual lane **120**. For example, the controller **102** may take the motion data of the vehicle **108** in the virtual lane **120** that is collected by the sensors **106** and begin calculating the velocity vector **116**, the distance **118**, and so forth, as described above.

55 In one embodiment, the virtual lane **120** may also help prevent false positives. For example, the vehicle **108** may be parking or collecting a package that is near the door **104**. However, with the virtual lane **120**, the door **104** may not be accidentally opened if the vehicle **108** were to move to the right side of the door **104** when the virtual lane **120** is located 60 on a left side of the door **104**.

In one embodiment, the virtual lane 120 may be combined with a predefined route. For example, the vehicle 108 may be collecting garbage that is near the door 104. Paths to the garbage near the door 104 in conjunction with the virtual lane 120 may be predefined such that the door 104 may be opened to allow the vehicle 108 to then exit through the door 104 to a dumpster that is outside of the location 114. In other words, the intention of the vehicle 108 may be detected to be associated with a predefined route once the vehicle 108 enters the virtual lane 120. Thus, although the vehicle 108 does not initially move towards the door 104, the controller 102 may open the door 104 such that the door 104 is opening as the vehicle 108 is approaching the door 104 after picking up the garbage near the door 104.

In one embodiment, the virtual lane 120 may also provide additional safety. For example, the door 104 may allow two-way traffic. In one embodiment, vehicles 108 may exit on a left side of the door 104 and vehicles 108 may enter on a right side of the door 104. As a result, if a vehicle 108 attempts to exit on the right side of the door 104, the vehicle 108 may not be in the virtual lane 120. As a result, the controller 102 may not be activated to perform calculations and control operation of the door. This may prevent another vehicle which may be entering through the door 104 from crashing into the vehicle 108 which may be trying to exit through the door 104.

In one embodiment, the boundaries of the virtual lane 120 may be predefined and stored in the controller 102. The controller 102 may determine if any of the motion data (that may include location data) from any of the sensors 106 associated with the vehicle 108 is within the predefined boundaries of the virtual lane 120 stored in the controller 102. In another embodiment, a subset of the sensors 106 may be focused on the virtual lane 120. Thus, when the subset of the sensors 106 detects motion within the area of focus (e.g., associated with the boundaries of the virtual lane 120), the controller 102 may be activated.

Although the virtual lane 120 improves the efficiency of controlling the door, the velocity data may be collected when the vehicle 108 is within the sensing area of the sensors 106. In other words, the sensing area may be defined as any area within the location 114 that is covered by the sensors 106.

The area outside of the virtual lane 120, but within the sensing area may be a passive monitoring zone. That is, the sensors may detect the presence of the vehicle 108, general movement and direction of the vehicle 108, and the like. The sensors 106 may collect velocity data on the vehicle 108 in the passive monitoring zone that can be used for other controls and/or emergency controls, such as opening a door to prevent an accident if the vehicle 108 is too close to a door despite being outside of the virtual lane 120 or if the vehicle 108 is moving above at a velocity that is above a velocity threshold towards the door. Thus, in some embodiments, velocity calculations may be collected outside of the virtual lane 120 for additional safety precautions and other controls.

As noted above, the controller 102 may calculate the velocity vector 116 based on the data from the sensors 106. The velocity vector 116 may include two components or values. One value may be the velocity or distance traveled per time (e.g., m/s, feet per second (ft/s), miles per hour (mph), and the like). A second value may be a directional value or component. The controller 102 may calculate the velocity vector 116 and determine whether the vehicle 108 is attempting to exit through the door 104 based on the directional component of the velocity vector 116.

In one embodiment, the controller 102 may account for a changing or variable velocity vector 116. For example, the

movement of the vehicle 108 may not be a constant velocity. In other words, as the vehicle 108 approaches the door 104, the velocity of the vehicle 108 may be inconsistent or changing. For example, the vehicle 108 may slow down as the vehicle 108 approaches a person crossing in front or as another vehicle may approach from an opposite direction. In another example, the operator of the vehicle 108 may not press on the accelerator with a constant pressure causing the vehicle 108 to speed up or slow down as the vehicle 108 approaches the door 104. Thus, as the vehicle moves by the sensors 106 the controller 102 may calculate a different velocity vector 116 at different points along the virtual lane 120 from different sets of sensors 106 along the virtual lane 120.

15 In one embodiment, the velocity vector 116 may be calculated based on the data from the sensors 106. For example, the velocity may be calculated based on data from one or more sensors 106. For example, the sensors 106 may be motion sensors that use lasers to calculate time of flight data using UWB, as described above. Based on consecutive readings, the sensors 106 may calculate the velocity vector 116 of the vehicle 108. The information may then be sent to the controller 102.

20 In one embodiment, the readings from the sensors 106 may be transmitted to the controller 102, and the controller 102 may calculate an estimated velocity. For example, the sensor 106₁ may measure a first distance of 10 feet to the vehicle 108 and a second distance of 20 feet to the vehicle 108 one second apart. Thus, the controller 102 may calculate that the vehicle 108 is moving at approximately 10 ft/s.

25 In another example, the first sensor 106₁ and the second sensor 106₂ may be 10 feet apart. The first sensor 106₁ may detect the vehicle 108 at time t=0. The second sensor 106₂ may detect the vehicle 108 at time t=5. Thus, the controller 102 may calculate that the vehicle 108 is moving at a velocity of 2 ft/s (10 feet/5 seconds).

30 In one embodiment, the direction may also be determined by the sensors 106. For example, the sensors 106₁, 106₂, 106₃, and 106₄ may collect data that indicates over time that the vehicle 108 is moving further away. However, the sensors 106₃ and 106₄ may collect data that indicates over the same period of time that the vehicle 108 is moving closer. As a result, the controller 102 may calculate that the vehicle 108 is moving towards the door 104. Also, when the direction is determined to be towards the door, the controller 102 may determine that the vehicle 108 is attempting to exit through the door 104.

35 In another embodiment, the sensors 106 may be image capturing devices. The sensors 106 may capture consecutive images of the vehicle 108. Pixel level analysis may be performed on the images to calculate directional vectors of each pixel to determine a direction in which the vehicle 108 is moving. In addition, based on the frame rate or image capture rate of the image capturing device and a distance traveled of a reference pixel between consecutive images, the controller 102 may calculate an estimated velocity of the vehicle 108.

40 Thus, the controller 102 may process the data collected by the sensors 106 when triggered by motion detected within the virtual lane 120. The controller 102 may calculate a velocity vector 116 using the data from the sensors 106. Based on the velocity vector 116, the controller 102 may determine if the vehicle 108 is attempting to exit through the door 104. If so, the controller 102 may calculate a time at which to begin opening the door 104 based on the velocity of the vehicle 108, a distance 118 of the vehicle from the door 104, and a time to open the door 104.

In one embodiment, the speed at which the door 104 is opened may be adjusted dynamically if the velocity vector 116 is variable, as described above. For example, based on a first calculated or initial velocity vector 116 at a first distance from the door 104, the controller 102 may determine a particular time to open the door 104. For example a first data set from a first set of sensors 106 may be used to calculate the initial velocity vector 116.

The vehicle 108 may continue moving along the virtual lane 120 and approach the door 104. At a second distance, the controller 102 may calculate an updated velocity vector 116 based on a second data set from a second set of sensors 106 that are located down stream (e.g., closer to the door 104) along the virtual lane 120. If the updated velocity vector 116 is different from the initial velocity vector 116, control of the door 104 may be adjusted.

For example, if the door 104 has not opened yet, the time at which the door 104 begins to open may be adjusted based on the updated velocity vector 116. If the door 104 has already begun opening, the speed at which the door 104 opens may be adjusted based on the updated velocity vector 116. For example, if the updated velocity vector 116 is slower than the initial velocity vector 116, the controller 102 may control operation of the door 104 such that opening speed of the door 104 is reduced to compensate for the later estimated time of arrival of the vehicle 108. In another example, if the updated velocity vector 116 is faster than the initial velocity vector 116, the controller 102 may control operation of the door 104 such that the opening speed of the door 104 is increased to compensate for the earlier estimated time of arrival of the vehicle 108.

In other words, the controller 108 may adjust a time or speed at which the door 104 is opened based on changes in the velocity vector 116 at different locations within the virtual lane 120. As a result, the operation of the door 104 may be adjusted dynamically based on the variable or changing velocity vector 116.

FIG. 2 illustrates a block diagram of the controller 102. In one embodiment, the controller 102 may be a server or a computing device. The controller 102 may include a processor 202, a memory 204, and a communication interface 214. The processor 202 may be communicatively coupled to the memory 204. The processor 202 may execute instructions stored in the memory 204 to perform the functions described herein.

In one embodiment, the memory 204 may be any type of non-transitory computer readable storage medium. For example, the memory 204 may be a hard disk drive, a solid state drive, a read only memory, a random access memory, and the like.

In one embodiment, the memory 204 may store vehicle information 206, sensor data 208, virtual lane coordinates 210, and door control rules 212. In one embodiment, the vehicle information 206 may include information associated with vehicles 108, which are allowed to exit through identified doors 104. For example, the vehicle information received from the RF tag reader 112 may be compared to the vehicle information 206 to determine a corresponding the vehicle 108 is authorized to exit through a particular door 104. For example, some vehicles 108 may be too big to fit through a particular door 104. Other vehicles 108 may not be authorized to exit through a particular door for security or safety reasons.

In one embodiment, the sensor data 208 may store the data received from the sensors 106. In one embodiment, the sensor data 208 may be temporarily stored. For example, the sensor data 208 may be deleted every hour to prevent too

much data from being stored. In one embodiment, the sensor data 208 may not be stored until the vehicle 108 is detected in the virtual lane 120 to save memory space in the memory 204. The processor 202 may then access the sensor data 208 to begin calculating the velocity vector 116, distance 118, and so forth.

In one embodiment, the virtual lane coordinates 210 may store the boundary of the virtual lane 120. The virtual lane coordinates 210 may be predefined and may include a range of values (e.g., within a two dimensional coordinate space associated with the location 114). The motion data from the sensors 106 may be continuously compared to the virtual lane coordinates 210. For example, the location data obtained from the data captured by the sensors 106 may be compared to the range of values stored in the virtual lane coordinates 210. If the location data is within the range of values, then the vehicle 108 may be determined to be in the virtual lane 120. The processor 202 may be activated, the data associated with the vehicle 108 in the virtual lane 120 may be stored in the sensor data 208, and the processor may begin performing additional calculations with the sensor data 208, as described above.

It should be noted that FIG. 2 has been simplified for ease of explanation. The controller 102 may include additional components that are not shown. For example, the controller 102 may include a display, a graphical user interface, input devices (e.g., a keyboard, a mouse, a trackpad, a touch-screen, and the like), other types of information stored in the memory 204, and the like.

FIG. 3 illustrates an example operation of the system 100. FIG. 3 illustrates the location 114 including all of the components of the system 100 illustrated in FIG. 1 and discussed above. For example, the system 100 may include the controller 102, the door 104 coupled to a motor 150, a plurality of sensors 106, and an RF tag reader 112.

In a first example, the vehicle 108 may be a forklift driven by an operator. The operator may want to exit the location 114. Thus, the vehicle 108 may move towards the door 104 and into the virtual lane 120. The location 114 may include other vehicles 122 and 124. Thus, the sensors 106 may be simultaneously collecting movement data of many different vehicles 108, 122, and 124 in and around the location 114.

However, when the vehicle 108 enters the virtual lane 120, the controller 102 may be activated to begin calculating a velocity vector based on data being collected from the sensors 106 for the vehicle 108. The controller 102 may then determine a time at which to begin opening the door 104. Based on the velocity vector of the vehicle 108 and the distance to the door 104, the controller 102 may open the door such that the vehicle 108 may exit without having to wait for the door 104 to open. In other words, the vehicle 108 may maintain a constant velocity in a current direction without having to slow down to wait for the door 104 to be opened. Other data which may be utilized may include the door height, motor force, motor speed, and the height of the vehicle.

In one embodiment, the controller 102 may also perform calculations to determine a time to begin opening the door 104 based on changes in the velocity vector. For example, the movement of the vehicle 108 may not be a constant velocity and the velocity vector may be variable. In other words, as the vehicle 108 approaches the door 104, the velocity of the vehicle 108 may be inconsistent or changing. For example, the vehicle 108 may slow down as the vehicle 108 approaches a person crossing in front or as another vehicle may approach from an opposite direction. In another example, the operator of the vehicle 108 may not press on

the accelerator with a constant pressure causing the vehicle **108** to speed up or slow down as the vehicle **108** approaches the door.

In another example, the door **104** may allow two-way traffic. Thus, another vehicle **122** may be trying to enter the location **114** through the door **104** and the vehicle **108** may be trying exit the location **114** through the door **104**. Another virtual lane **130** may be predefined opposite the virtual lane **120** on the opposite side of the door **104**, as shown in FIG. 3. The virtual lane **130** may operate and function similar to the virtual lane **120**.

As a result, the door **104** may not be opened unless both the vehicle **108** and the vehicle **122** are in the respective virtual lanes **120** and **130**. Thus, controller **102** may keep the door **104** closed if the sensors **106** detect the vehicle **122** approaching directly in front of the vehicle **108**. Thus, a collision may be avoided. In one embodiment, the controller **102** may transmit a message to both the vehicle **108** and the vehicle **122** indicating why the door **104** is not opening. As noted above, the vehicles **108** and **122** may include communication modules. The IP addresses for the communication modules can be read from the RF tags **110**, and the controller **102** may address the message to the respective IP addresses.

In another example, the vehicle **124** may be approaching the door **104**. The vehicle **124** may be attempting to pick up an item from a shelf **126** that is located adjacent to the door **104**. In one embodiment, the vehicle **124** may initially have started in the virtual lane **120**. As a result, the controller **102** may be activated. The controller **102** may calculate the velocity vector of the vehicle **124**. However, the directional component of the velocity vector may indicate that the vehicle **124** is turning towards the shelf **126**. Thus, the controller **102** may determine that the vehicle **124** is not attempting to exit through the door **104** and may keep the door **104** in a closed position. As a result, a false positive may be avoided and the door **104** may remain in a closed position.

In another example, a predefined route may be associated with the movement towards the shelf **126**. For example, objects on the shelf **126** may be picked up and taken to a particular location outside of the location **114**. Thus, the vehicle **124** may be approaching the door **104** to pick up an item on the shelf **126**. The controller **102** may calculate the velocity vector, or receive the velocity vector from the sensors **106**, of the vehicle **124**. The directional component of the velocity vector may indicate that the vehicle **124** is turning towards the shelf **126**. The controller **102** may recognize that this movement is associated with a predefined route. Thus, the controller **102** may continue to track movement of the vehicle **124** and may determine a time at which to begin opening the door **104**.

It should be noted that the above scenarios are provided as examples and should not be considered limiting. Other scenarios may be understood to be part of the present disclosure and within the scope of the present disclosure.

FIG. 4 illustrates a detailed flow chart of an example method for controlling a door of the present disclosure. In an example, the method **400** may be performed by the server or controller **102**, or by the apparatus **500** illustrated in FIG. 5, and described below.

At block **402**, the method **400** begins. At block **404**, the method **400** determines that a vehicle is approaching a door of a building based on a velocity vector of the vehicle. For example, the vehicle may be trying to exit or enter the building through the door. In one embodiment, a processor or controller may be activated when the vehicle enters a

virtual lane. When activated, the processor may analyze motion data or information collected from sensors deployed throughout the building.

In one embodiment, the velocity vector may include a velocity or speed component and a directional component. The directional component may indicate whether the vehicle is attempting to exit the building, trying to turn towards a shelf located near the door, or the vehicle was moving across the building, but happened to cut through the virtual lane.

In one embodiment, the velocity vector may be variable. Thus, multiple velocity vectors may be calculated based on data from different sets of sensors at different locations along the virtual lane.

In one embodiment, if it is determined that the vehicle is attempting to exit the building through the door, the processor may determine if the vehicle is authorized to exit through the door. For example, the vehicle may have an RF tag that can be read by an RF tag reader. The RF tag may include information associated with the vehicle. The information may be compared to stored information to determine if the vehicle is authorized. If the vehicle is not authorized to exit through the door, a message or notification may be transmitted to the vehicle.

At block **406**, the method **400** calculates a time of arrival of the vehicle at the door based on the velocity vector of the vehicle and a distance of the vehicle from the door. For example, the velocity vector may include a velocity component, as noted above. The distance may be determined based on data collected from the sensors. For example, the vehicle may be moving at 5 ft/s and the sensors may measure that the vehicle is 30 feet from the door. Thus, the time of arrival of the vehicle may be 6 seconds.

In one embodiment, the time of arrival may be adjusted dynamically as the vehicle approaches the door. As noted above, the velocity vector may be variable. Thus, the velocity vector may be calculated as the vehicle passes each set of sensors within the virtual lane to determine if the time of arrival should be updated. A distance threshold may be predetermined where the time of arrival can no longer be changed and the time of arrival is set to the last time of arrival that was calculated based on the last velocity vector that was calculated.

At block **408**, the method **400** controls the door to begin opening at a time based on the time of arrival and an amount of time for the door to open such that the door is opened when the vehicle arrives at the door. Using the example above, the door may take 4 seconds to open. Thus, the processor may begin opening the door in 2 seconds such that the door may be opened when the vehicle arrives at the door at its current velocity. For example, after 2 seconds, the vehicle would reach the door in 4 seconds. Since the door takes 4 seconds to open, the door would be opened when the vehicle arrived at the door.

In one embodiment, the control of the door may be adjusted dynamically based on a variable velocity vector. For example, an updated velocity vector of the vehicle may be calculated as the vehicle moves through the virtual lane. The updated velocity vector may be different than the initial velocity vector that was calculated. The control of the door may be adjusted based on the updated velocity vector. For example, the door may be controlled to open more slowly or more quickly based on the updated velocity vector. For example, if the updated velocity vector is greater than the initial velocity vector after the door begins opening, the door may be controlled to open more quickly. Conversely, if the

11

updated velocity vector is less than the initial velocity vector after the door begins opening, the door may be controlled to open more slowly.

In one embodiment, the method 400 may also determine if the vehicle has cleared the door. Once the vehicle has cleared the door, the door may be controlled to close in response to the vehicle being clear of the door. As a result, the method 400 may automatically open and close the door based on the movement of the vehicles. At block 410, the method 400 ends.

FIG. 5 illustrates an example of an apparatus 500. In an example, the apparatus 500 may be the server or controller 102. In an example, the apparatus 500 may include a processor 502 and a non-transitory computer readable storage medium 504. The non-transitory computer readable storage medium 504 may include instructions 506, 508, 510, 512, and 514 that, when executed by the processor 502, cause the processor 502 to perform various functions.

In an example, the instructions 506 may include instructions to determine that a vehicle is in a virtual lane associated with a door. The instructions 508 may include instructions to calculate a velocity vector of the vehicle. The instructions 510 may include instructions to determine that the vehicle is approaching the door. The instructions 512 may include instructions to calculate a time of arrival of the vehicle at the door based on the velocity vector of the vehicle and a distance of the vehicle from the door. The instructions 514 may include instructions to control the door to begin opening at a time based on the time of arrival and an amount of time for the door to open such that the door is opened when the vehicle arrives at the door.

It will be appreciated that variants of the above-disclosed and other features and functions, or alternatives thereof, may be combined into many other different systems or applications. Various presently unforeseen or unanticipated alternatives, modifications, variations, or improvements therein may be subsequently made by those skilled in the art which are also intended to be encompassed by the following claims.

The invention claimed is:

1. A system, comprising:
a door;
a motor to control operation of the door;
a controller communicatively coupled to the motor to control operation of the motor to open and close the door; and
a plurality of sensors communicatively coupled to the controller to collect movement data of a vehicle, wherein the controller is to calculate an initial velocity vector of the vehicle based on the movement data and to cause the motor to begin opening the door at a first speed at a time based on a time of arrival of the vehicle at the door that is calculated from the initial velocity vector and a distance of the vehicle from the door, and based on an amount of time for the door to open such that the door is opened when the vehicle arrives at the door, to determine an updated velocity vector of the vehicle, and to adjust operation of the door that has begun opening to open at a second speed based on the updated velocity vector, wherein the second speed of the door opening is different than a first speed of the door opening.
2. The system of claim 1, wherein a first data set from a first set of the plurality of sensors is used to calculate the initial velocity vector and a second data set from a second set of the plurality of sensors is used to calculate the updated velocity vector.

12

3. The system of claim 1, wherein the controller is to adjust operation of the door based on the updated velocity vector by increasing or decreasing the second speed at which the door is opened.

5 4. The system of claim 1, wherein the plurality of sensors comprises laser sensors that capture the movement information based on time of flight data.

10 5. The system of claim 1, wherein the plurality of sensors uses an ultra-wideband (UWB) communications protocol to receive information from a tag on the vehicle to calculate the distance of the vehicle from the door.

15 6. The system of claim 1, wherein the plurality of sensors comprises an image capturing device to capture image data of the vehicle, wherein the movement information is calculated based on an analysis of the image data.

7. A method, comprising:
determining, by a processor, that a vehicle is approaching a door of a building based on an initial velocity vector of the vehicle;

20 calculating, by the processor, a time of arrival of the vehicle at the door based on the initial velocity vector of the vehicle and a distance of the vehicle from the door;

25 controlling, by the processor, the door to begin opening at a first speed at a time based on the time of arrival and an amount of time for the door to open such that the door is opened when the vehicle arrives at the door; determining, by the processor, an updated velocity vector of the vehicle; and

30 adjusting, by the processor, the controlling of the door that has begun opening to open at a second speed based on the updated velocity vector, wherein the second speed of the door opening is different than a first speed of the door opening.

35 8. The method of claim 7, wherein determining that the vehicle is approaching the door is performed when the vehicle is determined to be within a virtual lane associated with the door.

40 9. The method of claim 8, wherein the virtual lane is associated with a predefined route.

10 10. The method of claim 7, wherein determining the updated velocity vector of the vehicle is performed using data collected by different sensors as the vehicle moves within a virtual lane associated with the door.

45 11. The method of claim 7, wherein adjusting the controlling of the door comprises changing the time of arrival.

50 12. The method of claim 7, wherein adjusting the controlling of the door comprises increasing the second speed to be greater than the first speed at which the door is opened when the updated velocity vector is greater than the initial velocity vector.

55 13. The method of claim 7, wherein adjusting the controlling of the door comprises decreasing the second speed to be less than the first speed at which the door is opened when the updated velocity vector is less than the initial velocity vector.

60 14. The method of claim 7, wherein the velocity vector comprises a velocity and a direction of the vehicle.

15 15. The method of claim 7, wherein the velocity vector is calculated based on data received from a plurality of sensors.

16. The method of claim 13, wherein the data comprises time of flight measurements using ultra-wide band (UWB) protocol by the plurality of sensors.

65 17. The method of claim 13, wherein the velocity vector is calculated based on image data received from the plurality of sensors.

13

18. A non-transitory computer readable storage medium encoded with instructions executable by a processor, the non-transitory computer-readable storage medium comprising:

instructions to determine that a vehicle is in a virtual lane associated with a door;

instructions to calculate an initial velocity vector of the vehicle;

instructions to determine that the vehicle is approaching the door;

instructions to calculate a time of arrival of the vehicle at the door based on the velocity vector of the vehicle and a distance of the vehicle from the door;

instructions to control the door to begin opening at a first speed at a time based on the time of arrival and an amount of time for the door to open such that the door is opened when the vehicle arrives at the door;

5

instructions to calculate an updated velocity vector of the vehicle at a different location within the virtual lane; and

instructions to adjust control of the door that has begun opening to open at a second speed based on the updated velocity vector, wherein the second speed of the door opening is different than a first speed of the door opening.

19. The non-transitory computer readable storage medium of claim **18**, wherein a first data set from a first set of sensors along the virtual lane is used to calculate the initial velocity vector and a second data set from a second set of sensors along the virtual lane is used to calculate the updated velocity vector.

20. The non-transitory computer readable storage medium of claim **18**, wherein the controller is to adjust operation of the door based on the updated velocity vector by increasing or decreasing the second speed that the door is opened.
